UNITED STATES PATENT OFFICE.

ALEXANDER M. MILLER, OF RIVERSIDE, CALIFORNIA.

SIGNAL.

Application filed March 9, 1928. Serial No. 260,429.

My invention relates to signals and an object thereof is to provide a signal whereby the driver of a motor vehicle may readily ascertain whether or not certain lights are functioning.

A further object of the invention is to provide an automatic electrically operated signal whereby the driver of a motor vehicle may ascertain whether or not the usual tail 10 and signal lights are functioning.

With the preceding and other objects and advantages in mind, the invention consists in the novel combination of elements, constructions and arrangement of parts to be 15 hereinafter specifically referred to, claimed and illustrated in the accompanying drawings, wherein:

Figure 1 is a perspective of parts of a motor vehicle with my invention applied thereto;

Figure 2 is a sectional view of the invention and illustrating the electrical wiring or circuit diagrammatically;

Figure 3 is a transverse sectional view of 25 the device; and

Figure 4 is a front elevation of the same removed from the motor vehicle.

Referring to the invention in detail a circular casing 5 open at the front and having 30 an annular flange 6 at its forward edge is provided, the casing being adapted to be supported on the instrument board of an automobile, as illustrated in Figure 1. A non-conducting disk 7 formed of bakelite or 35 other analogous material is received in the casing 5. Pairs of transversely aligned openings 8 are provided in the disk 7 through which binding posts 9 pass and project from the outer face of the rear wall of the casing. 40 An insulation element 10 is interposed between the disk 7 and casing, through which the binding posts pass to insulate the latter from the casing.

Supported upon the outer face of the disk 45 between the pairs of openings 8 is a pair of opposed solenoids 11, each of which is received on a bracket 12 attached to the disk. These solenoids are arranged in divergent 50 relation and the winding of each is electrically connected with one pair of the binding posts, as at 13.

Arranged between the opposed faces of the solenoids and secured to the disk 7 is a vertically arranged U-shaped bracket 14 having 55 a right angular extension 15 at its upper end that lies parallel with its intermediate leg.

Horizontally disposed parallel rock shaft 16 are journalled between the intermediate leg of the U-shaped bracket and the extension 15 and are arranged with their outer ends projecting beyond this bracket. An armature 17 for each of the solenoids is attached to each of the rock shafts. These armatures are relatively flat and are normally suspended in a vertical position.

To prevent either of the solenoids from attracting both of the armatures a vertically arranged stop 18 is disposed between the free ends of the armatures. This stop 18 consists of a length of metal bent into inverted 70 T-shape formation and has its horizontal branch received on the lower horizontal leg of the U-shaped bracket.

A dial 19 is received in the open end of the casing and carries laterally projecting resilient U-shaped guides 20 at diametrically opposite points on its inner face which receive the parallel legs of the U-shaped bracket to hold the dial in place. A resilient clamping ring 21 received in the outer end of the casing, engages the dial and cooperates with the resilient guides 20 in holding the dial in place. An indicating hand 22 is carried by the outer end of each of the rock shafts and is movable over the outer face of the 80 dial, as illustrated in Figure 4. These indicating hands are normally disposed in a perpendicular position where they register with zero marks 23 at the lower edge of the dial. The phrases "Tail light" and "Stop 85 light" are inscribed upon the dial upon opposite sides of the zero marks.

An opaque closure glass 24 is held in the open end of the casing by a retaining ring 25 surrounding the glass and engaged with 90 the annular flange. The closure 24 is provided with a segmental shaped transparent area 26 overlying the indicating hands 22 and indicia.

The binding posts 9 are connected in series 100 with a foot brake actuated stop light signal and a tail light as illustrated in the electrical diagram disclosed in Figure 3. It will be observed that when the switches in the circuit are open the armatures will be permitted to depend in a perpendicular position and consequently cause the indicating hands to coincide with the zero marks 23. However, when either the tail light or brake signal switch is actuated to complete an electrical circuit, the coinciding solenoid will 105 be energized to attract the corresponding 110

armature and thereby swing its indicating hand to a position to overlie the phrases "Tail light" or "Stop light", as the case may be. Should, for any reason, the circuit to either the tail light or stop signal be incomplete, the corresponding indicating hand will remain in a perpendicular position, thus indicating to the motorist that such light or signal is not functioning.

10. What is claimed is:—

1. In a signal device a casing, a bracket supported within the casing, a pair of parallel horizontally disposed rock shafts supported by the bracket, an armature extending from each rock shaft, a vertically disposed spacing element arising from the bracket and extending between the armatures and normally contacted by the latter, an indicating hand fixed to each of the rock shafts, and solenoids supported in the casing opposite to each armature, and when energized causing movement of the armatures to correspondingly move the indicating hands.

2. In a signal device a casing, a bracket supported therein having a laterally projecting part, a pair of pivoted armatures

supported on the bracket above the laterally projecting part, indicating hands movable with the armatures, solenoids supported within the casing opposite the armatures, a loop removably received on the laterally projecting part of the bracket and carrying an upstanding spacer member which extends between the armatures.

3. In a signal device a casing, a substantially U-shaped bracket supported within the casing, electro-magnets also supported within the casing upon the opposite sides of the bracket, pivoted signal elements supported by the bracket and operated to signalling position upon energization of the solenoids, a dial received in the casing and over which the signal elements move, and opposed channel-shaped slips projecting laterally from the inner face of the dial and engaging the parallel legs of the bracket to hold the dial in place.

Signed at Riverside, in the county of Riverside, and State of Calif., this 28th day of February A. D. one thousand nine hundred and twenty-eight.

ALEXANDER M. MILLER.
